UNITED STATES PATENT OFFICE.

F. BENEDICT HERZOG, OF NEW YORK, N. Y.

BELL FOR LATENT-SIGNAL TRANSMITTERS.

SPECIFICATION forming part of Letters Patent No. 315,941, dated April 14, 1885.

Application filed March 5, 1885. (No model.)

To all whom it may concern:

Be it known that I, F. BENEDICT HERZOG, a citizen of the United States, residing at New York, in the county and State of New York, 5 have invented a new and useful Improvement in Bells for Latent-Signal Transmitters, of which the following is a specification.

In Letters Patent No. 289,834, issued to me December 11, 1883, I have described an automatic variable electric signaling instrument applicable to telephone and many other uses, the main feature of which is that, although the instrument may be "set" at one station to transmit a desired signal to another, yet 15 the signal when so set will not be sent to the receiving-station by the sending-operator or by the act or at the moment of setting it, as is the case in all instruments of the kind known generally as "transmitters;" but my instrument retains the signal asset in a "latent" state ready to be released until it is so released directly or indirectly from the receiving-station by the operator, who, if he desires to discover at what signal the instrument is set, actuates 25 certain "releasing" mechanism, whereupon if the instrument has been set to transmit any signal, that signal would be transmitted to the receiving-station without any further co-operation of the sending-operator after he has once 30 prepared the signal. In this and in contemporaneous applications I call such an instrument a "latent-signal transmitter," for the reason that the signal so set remains latent until released by the action of the receiving-operator.

My present invention relates, principally, to the application of such apparatus to hotels, in which each guest's room is furnished with such a latent-signal transmitter electrically connected with the clerk's office, by which the guest can signal to the hotel-clerk his various wants. The guest can set this instrument at pleasure, and can then signal to the hotel-clerk by an annunciator that his instrument has been set, whereupon the clerk, as soon as he is prepared to receive the signal, can release the guest's instrument and receive its signal.

In an application, Serial No. 148,374, filed 50 November 20, 1884, of which application the present is a division, I have described and claimed such a system of call-circuits in which

I employ two separately-operative circuits connecting the guest's room or calling-offices with the clerk's or receiving office, one circuit 55 being employed to release the transmitter and receive the guest's signal, and the other circuit being employed as a signaling-circuit to signal to the clerk that a guest has set his instrument; but to avoid the necessity of having two separate circuits to each of the guests' rooms for this purpose, I employ only a single set of individual circuits extending to each room and two distinct common return-circuits, one for releasing and transmitting the 65 guest's signal and the other for calling the clerk's attention, as described and claimed in the last-named application.

In another application (Division B of the above-named application) I have described 70 and claimed a further improvement upon the system described and claimed in this last-named application, Serial No. 148,374, which consists in so constructing and connecting the guest's transmitter that the mere act of setting the instrument automatically signals to the clerk by means of the annunciator that the instrument has been set, as therein described, thus making it unnecessary for the guest to press a separate push-button or circuit-changer in order to call the attention of the clerk to the fact that the instrument is set.

The main object of my present invention is to provide means by which the hotel-clerk can at any moment operate a bell or call in 85 the guest's room for the purpose of calling or waking him at any hour or in case of fire, and still not cause it to sound more often than required, or not at all, if desired at any time.

To this end my invention consists, first, in 90 arranging in the guest's room and in the transmitter-circuit an electric bell or call, so that it can be rung by the clerk from the office when specially desired, and at the same time in providing means by which this bell or call 95 may readily be rendered operative or inoperative by the guest or any other person at pleasure, in case it is desired only to use it occasionally; and, secondly, in so connecting the bell and so constructing the transmitter 100 itself that the mere act of setting it to transmit some signal automatically disconnects this bell from the circuit, (if it has been placed therein,) and so that it remains inoperative

until the instrument has been released and has completed the transmission of its signal, and so that when this has so completed its signal the bell is automatically reconnected in 5 circuit, thus not unnecessarily disturbing the guest.

In the drawings, Figure 1 represents the arrangement of circuits, showing my invention as applied to a hotel or similar central-office 10 system. Fig. 2 is a front view of my latent-signal transmitter with the front of the case partially removed, and showing its mechanism.

Each guest's room or branch office (as many as desired) is connected by a separate circuit, 15 *a c, &c.*, with the central or clerk's office situated either in the same or another building. Each of these individual circuits includes a latent-signal transmitter, *A C, &c.*, and a circuit-changing button or key, *d f, &c.*, placed 20 in the guest's room, and a circuit-changing device or spring-jack, *D F, &c.*, and an annunciator, *H J, &c.*, placed at the clerk's office. After passing through the annunciators 25 all the circuits unite, as shown, and then lead through an electric bell, *K*, which rings, and continues to ring, if desired, when the annunciator is dropped in order to call the attention of the clerk. From this bell the circuit leads 30 through a battery, *L*, of sufficient strength to work the annunciators in the usual manner, the other end of which is connected either with a ground or metallic return circuit, *l*, which also extends to and connects with all 35 the guests' rooms, as shown. This return-wire, together with the separate annunciator-circuits to each room, forms a complete annunciator system, by which any guest can call the clerk by simply depressing his key *d f, &c.*, the effect of which is to close his individual circuit by 40 connecting it with the common return-circuit, as clearly seen from the drawings. Normally the keys *d f, &c.*, connect with their upper contact-points, as shown, so that the individual circuit leads through the guest's transmitter *A C, &c.*, and thence through a common return-circuit, back to the clerk's office, whence it leads through a battery, *M*, a switch 45 and a receiving-instrument, *N*, the other end of this instrument being connected to the spring-jack plug *n*, insulated on the underside, so that by thrusting this plug into any particular spring-jack the individual circuit is 50 broken through the annunciator and connected with the receiving-instrument *N* and battery *M*. The latent-signal transmitter consists of the clock-work transmitter shown in detail in Fig. 2, the signal being transmitted by a break-wheel in circuit in the well-known manner, and the escapement being controlled by 55 an electro-magnet also included in the circuit, as shown, and as fully described in an application filed by me in the Patent Office, September 29, 1884, and to which reference is 60 made for details that do not affect my present 65 invention.

The operation of my hotel system will now be understood. Suppose a guest wishes to

call for a fireman, for example. By means of a knob (not shown) attached to the spindle *O* he turns the spindle to the right, thereby moving the pointer *X* to the right until it rests over the word "Fireman" on the dial, and then presses the calling-key *d*, which of course may be made in the form of a push-button, or made a part of the transmitter for convenience, if preferred. This operates the corresponding annunciator, *H*, and calls the attention of the clerk. The clerk thereupon, as soon as he is ready to receive the signal, introduces the plug *n* in the spring-jack *D*, which introduces 75 the battery *M* and receiver *N* into the circuit and causes the guest's transmitter to be released and send in its conventional signal, which will be understood by the clerk, and in this case will mean "fireman." A sounder, or 80 any kind of receiving-instrument *N*, may be used; but I prefer to employ a visual indicator provided with a dial and pointer, as shown, which follows the pointer of the transmitter, and is driven by it step by step in the 85 well-known manner, so that the clerk is enabled to see at a glance, without counting, what the signal is, thus avoiding mistakes and saving time. As there is normally no current in 90 any of the transmitter-circuits (the return-circuit *m* being open at the clerk's office) the transmitters may be set, and will remain so without being released when the keys *d f, &c.*, are depressed to call the clerk's office, these 95 keys simply acting to close the individual circuits through the common return-circuits *l* without affecting the transmitters, which are 100 operated on an independent return-circuit, *n*. According to this system any number of guests 105 may set their transmitters at once, because the signals are not sent until the clerk is ready to receive them, when he releases them one by one, as desired. By observing the return of the pointer of his transmitter, or by listening to the noise of the clock-work as it unwinds, 110 or to the noise made by the armature in moving, the guest is informed that his instrument has been released, and that his want is known to the clerk.

The apparatus thus far described is particularly described and claimed in the applications before referred to, and I do not therefore claim this apparatus in this application.

My present invention consists in arranging a calling-bell in each guest's room, so that he 120 may be called or awakened at any time by the clerk. I will now describe this by reference to Fig. 2 and to the transmitters *C* of Fig. 1. I include in the circuit of the transmitter an electric bell or call, *E*, of any approved description, and capable of being operated in any desired manner by a proper current from the clerk's office. Furthermore, in order that this bell may be removed from circuit, so as not to interfere with the operation 125 of the transmitter, receiving apparatus at the office, or to disturb the guest when he does not wish to hear its sound, I interpose in the circuit a cut-out, *q*, within the trans-

mitter-box, and connect the ends of the bell by wires or flexible conductors to a double-faced plug, P, by thrusting which into the cut-out the bell may be instantly cut into the circuit at any time, as will clearly be seen from the drawings. From the cut-out *q* the circuit leads through the electro-magnet, and then through the transmitting-spring and break-wheel, and thence to the key *f*, as shown. As it may often be desirable that the bell should remain permanently in circuit, except when the transmitter is set to transmit a signal, in which case it should be rendered inoperative, so as not to interfere with the correct transmission and reception of the signal, I have devised an arrangement whereby the bell is automatically disconnected from circuit by the act of setting the instrument, and reconnected when the instrument is released and has finished sending its signal. To accomplish this result, I fix to the setting-spindle *O* an arm, *R*, which, when the instrument is unset, as shown, bears against the spring and holds it clear of the contact-point *s*. When the instrument is set, the arm is turned to the right, thus allowing the spring *S* and contact-point to connect and cut out or short-circuit the bell-circuit, (and the bell, if it be in circuit,) as clearly shown in the drawings, which short-circuit connection is again automatically broken when the instrument unwinds and the arm returns to its original position and raises the spring clear of its contact-point. The spring, however, is set and adjusted so as not to be raised off from the contact-point until after the break-wheel has completed the signal, so that, should the current in circuit be sufficiently strong to operate the bell when cut in circuit, it could not interfere with the signal.

I have particularly shown and described my invention as applied to one of the forms of my latent-signal transmitter; but after the above explanation it will readily suggest itself to those skilled in the art that it can be applied to other forms thereof and to other kinds of signaling-instruments, and I therefore do not confine myself to the arrangement shown.

What I claim as my invention, and desire to secure by Letters Patent, is—

1. The combination, at a sending-station, of a latent-signal transmitter, a bell or call receiving apparatus to be actuated from a distant station, a call-transmitting apparatus, and a circuit-controller by which the call-transmitter may be operated without releasing the latent-signal transmitter if set, substantially as described.

2. The combination of a latent-signal trans-

mitter and a bell or call at a sending-station, a circuit-controller at a distant station for releasing the latent-signal transmitter and operating the call, and circuit-connections between the two stations, together with a cut-out at the sending-station, whereby the bell may be cut out when desired, substantially as described. 65

3. The combination of a latent-signal transmitter, calling apparatus for actuating receiving apparatus at a distant station, a bell or call receiving apparatus, and a cut-out therefore at each of two or more sub-stations, a circuit-controller at a central station for releasing the latent-signal transmitter and operating the call, and an annunciator for receiving the calls from the sub-stations, and circuit-connections between the two stations, together with means at the central station for operating any desired call provided that it is in circuit, substantially as described. 70 75

4. The combination, at a sending-station, of a latent-signal transmitter, call-receiving apparatus, a circuit-controller, and electrical connections whereby the call-receiving apparatus is automatically cut out of circuit by the operation of setting the latent-signal transmitter, substantially as described. 80 85

5. The combination, at one station, of a latent-signal transmitter, call-receiver, circuit-controller, and electrical connections whereby the call-receiver is always out of circuit during the operation of the latent-signal transmitter and is automatically cut in again after the signal-transmitter has sent its signal, 90 95

6. The combination, at one station, of a latent-signal transmitter, a call-receiver, a circuit-controller, and electrical connections whereby the call-receiver is automatically cut 100 out of circuit by the act of setting the latent-signal transmitter to transmit its signal, remains out of circuit during the operation of the latter, and is again automatically cut into circuit when the transmitter has finished sending its signal, substantially as described. 105

7. The combination, at one station, of a latent-signal transmitter, call-receiver, and manually-operated cut-out, together with a circuit-controller and electrical connections, 110 whereby the act of setting the latent-signal transmitter automatically cuts out the call-receiver during the operation of the latent-signal transmitter, if, during such operation, it is in circuit of the manually-operated cut-out, substantially as described. 115
